UNITED STATES PATENT OFFICE.

JOHN E. FRYE, OF BOSTON, MASSACHUSETTS.

GAS-TIP.

No. 905,167.

Specification of Letters Patent.

Patented Dec. 1, 1908.

Application filed January 20, 1908. Serial No. 411,744.

To all whom it may concern:

Be it known that I, JOHN E. FRYE, citizen of the United States, residing at Boston, in the county of Suffolk and State of Massachusetts, have invented certain new and useful Improvements in Gas-Tips, of which the following is a specification.

The present invention relates to certain new and useful improvements in gas lighting appliances and more particularly to an improved burner provided with a novel check for regulating the supply of gas to the tip.

It is a fact of common knowledge that the effective pressure at various gas burners of the same system varies to such an extent that many of the burners are subject to such an excessive pressure as to cause the escape of more gas than is consumed, thereby occasioning a useless waste of gas and vitiating the atmosphere.

The object of the present invention has been to provide a simple and inexpensive check device by means of which the flow of gas through the individual burners may be regulated as required by the existing condition.

For a full understanding of the invention and the merits thereof and also to acquire a knowledge of the details of construction and the means for effecting the result, reference is to be had to the following description and accompanying drawings, in which:

Figure 1 is a perspective view of a gas burner embodying the invention. Fig. 2 is a longitudinal sectional view through the same. Fig. 3 is a transverse sectional view.

Corresponding and like parts are referred to in the following description and indicated in all the views of the drawings by the same reference characters.

Specifically describing the present embodiment of the invention the numeral 1 designates the burner base which is designed to be applied to a chandelier or like member. This base is preferably formed from an integral piece of material and has the upper end thereof closed by a transverse partition 2 provided with a central opening and also with a series of perforations 3, four of these perforations being shown in the present construction. An annular shoulder 4 is formed upon the exterior of the base 1 a slight distance below the upper end thereof, and the portion of the base above this shoulder is

exteriorly threaded as indicated at 5 to receive a tip 6 the lower end of which is designed to abut against the shoulder when the tip is screwed into position. This tip 6 may be formed of any suitable material although cast iron is preferably employed owing to the durable nature of that metal, and the said tip is formed with a transverse slit 7 through which the gas is adapted to issue and be consumed in the usual manner. Co-operating with the transverse partition 2 at the upper end of the base is a rotary disk 8 provided with perforations 9 corresponding to the perforations 3 of the partition and designed to be turned either into or out of registry with the same. Projecting downwardly from the central portion of the disk 8 is a pivot stud 10 designed to be received within the central opening of the partition 2, and the said stud may either be threaded within the opening or may have the extremity thereof upset as may be found the most convenient in manufacture. The upper portion of the disk 8 gradually decreases in thickness toward the periphery thereof and is formed at its central portion with a transverse slot 11 designed to receive a screw driver or similar tool employed for rotating the disk.

In the formation of the device it will be readily apparent that should the gas pressure at the burner be excessive so as to cause a waste of the gas, the disk 8 can be turned to throw the perforations therein only in a partial registry with the perforations of the transverse partition 2, thereby reducing the flow of gas through the burner to the required extent and preventing the waste. However, should the pressure of gas not be excessive the disk 8 can be adjusted to throw the perforations 9 and 3 in a full registry with each other, thereby permitting an unobstructed flow of the gas.

Having thus described the invention, what is claimed as new is:

In a gas burner, the combination of a tubular base closed at its upper end by a transverse partition provided with a central opening and also with a series of perforations surrounding the central opening, a tip applied to the tubular base, and a rotary disk mounted upon the transverse partition at the upper end of the base, one side of the rotary disk being provided with a centrally disposed pivot stud which is loosely received

within the central opening of the partition, while the opposite side of the disk gradually decreases in thickness toward the periphery thereof, the central and thicker portion of the disk being formed with a transverse slot for engagement with a tool for turning the disk, while the thinner edge portions of the disk are formed with perforations adapted

to be moved into or out of registry with the perforations in the partition. 10

In testimony whereof I affix my signature in presence of two witnesses.

JOHN E. FRYE. [L. s.]
